UNITED STATES PATENT OFFICE.

CLYDE C. COOK, OF SHERIDAN, WYOMING.

GATE AND OPERATING MEANS THEREFOR.

Application filed April 25, 1923. Serial No. 634,543.

To all whom it may concern:

Be it known that I, CLYDE C. COOK, a citizen of the United States, residing at Sheridan, in the county of Sheridan and State of Wyoming, have invented certain new and useful Improvements in Gates and Operating Means Therefor, of which the following is a specification, reference being had to the accompanying drawings.

10 This invention relates to gates, and particularly to means for opening and closing gates.

15 The general object of the invention is to provide a gate which is mounted upon a track for lateral movement with reference to the road, and provide very simple means whereby the gate may be shifted to its open position or shifted to its closed position by means of cables disposed in convenient position to the operator.

20 A further object is to provide a construction of this character wherein the track is a tilting track, that is pivoted midway of its ends, so that after the gate has been started either toward its full open position or toward its fully closed position, the weight of the gate will cause the track to tilt downward at that end toward which the gate is moving so that the gate will then 30 run by gravity down the track until it is fully opened or fully closed.

25 A still further object is to provide means under these circumstances which will hold the gate in either its opened or its closed positions.

35 Other objects have to do with the details of construction and arrangement of parts as will appear more fully hereinafter.

40 My invention is illustrated in the accompanying drawings.

Figure 1 is a perspective view of a gate constructed in accordance with my invention and showing the position of the parts with the gate closed;

45 Figure 2 is a fragmentary detail elevation of the upper portion of the gate operating mechanism showing the manner in which the gate is operated;

50 Figure 3 is an end elevation of the construction shown in Figure 2.

55 Referring to these drawings, it will be seen that there is disposed at one side of the roadway a pair of upright posts 10 which may be connected at their upper ends in any suitable manner and pivoted between

these upright posts and extending laterally in opposite directions approximately the length of the gate is the track 11. This track is pivoted at 12 and is formed at its middle with a depressed portion 13. The 60 ends of the track operate vertically in posts 14 which are formed at their upper ends with vertical slots or openings 15, between which the free ends of the track are guided.

The gate 16 is carried by hangers 17, the 65 upper ends of these hangers carrying wheels 19 and 19^a which operate upon the track. The gate, of course, operates between the posts 10 and is freely slidable along the track. When the gate is closed the wheel 19 70 engages in the depression 13 and when the gate is opened the wheel 19^a engages in this depression, thus holding the gate from accidental movement from either its closed or its open position.

75 Pivoted upon the upper ends of the posts 10 and between the posts is a double bell crank lever 20 pivoted at 21 and having a downwardly extending arm 22 which is preferably formed with two oppositely and downwardly curved extremities which extend down into the depressed portion 13 of the track. Mounted upon the uprights 10 below the track are outwardly extending hangers or supports 23 carrying pulleys 24. 80 Attached to each arm of the lever 20 are chains or other flexible connections 25 and 26. These extend downward through the pulleys 24 and then downward to a position on each side of the gate and pass over pulleys 27 mounted upon posts 28. There is one of these posts disposed on one side of the gate and another post on the opposite side of the gate. The chains or flexible connections 25 from one end of the lever 20 85 pass downward onto opposite sides of the gate, while the chains 26 from the opposite end of the lever pass down to opposite sides of the gate. The chains 25 are for the purpose of opening the gate. The chains 26 90 are for the purpose of closing the gate.

95 With this construction, it is obvious that assuming the gate is closed, as shown in Figure 1, then a pull upon one of the chains 25 will depress the end of the lever 20 to 100 which the chain is connected. This will cause the arm 22 to move to the dotted line position and lift up on the wheel 19 and shift the gate toward the left in Figure 1. As soon as the wheel 19 has been lifted out of the 110

recess 13 and the gate has been slightly shifted to the left, the track will be overbalanced and tilted downward at its left end and as a consequence the gate will run from its closed 5 to its open position. This will bring the wheel 19^a into the recess 13 and obviously this wheel will be on the right hand side of the depending arm of the lever 20. After the person has passed through the gate one 10 of the operating cables 26 is pulled, which will shift the arm 22 to the right in Figure 1, lifting the wheel 19 out of the depression 13 and starting the gate toward the right and as soon as the gate has moved slightly toward the right it will cause the depression of the right hand end of the track and the gate will move downward by gravity toward this right hand end until the gate is again closed.

It will be seen that with this construction 20 only a slight effort has to be applied by the person to open or close the gate in order to start the gate toward its open or closed position and that then the gate rolling down the tilted track will automatically move without the exercise of any effort to its open or closed position. It will likewise be noted that when the gate has arrived at its fully open or its fully closed position, one of the wheels will rest in the depression 13, while 25 the other wheel will be on a level with the first named wheel, due to the downward tilting of the track, so that the gate is thus at all times held in a horizontal position.

I obviously do not wish to be limited to 25 the details of construction and the detailed arrangement of parts, as it is obvious that these may be changed in many ways without departing from the spirit of the invention.

I claim:—

40 1. A gate construction of the character described comprising a vertical member, a track pivoted thereon and extending on each side of the vertical member, the track having a depression at its pivotal center, a gate having 45 wheels running on said track, one of said wheels normally resting within the depressed portion of the track, means limiting the downward movement of the ends of the track, and manually operable means for lifting 50 the gate and one of said wheels from the depression and starting it along said track.

55 2. In a gate structure, an upright member, a track having its middle portion depressed and the track being pivoted to said upright member at its middle, wheels operating along the track, hangers depending from the wheels, a gate mounted upon said hangers, means limiting the downward movement of 60 the track at its outer ends, a vertical lever pivotally mounted above the track at the middle thereof and having a depending arm adapted to engage the wheel of the gate which is in said depression, and manually

operable means for oscillating said lever in 65 one direction or the other.

3. In a gate structure, a post, a track having its middle portion depressed and pivoted to said post, the track extending in opposite directions from the post, means for limiting the downward movement of both ends of the track, a T-shaped lever pivoted at its upper end to said post and having a depending arm, a gate, hangers supporting the gate and having wheels operating on said track, one of said wheels normally resting in said depressed portion of the track, an oscillation of the T-shaped lever causing its arm to engage the wheel which is in said depression and lift said wheel onto the track and impel the gate toward one or the other end of the track, and manually operable means for oscillating said lever.

4. In a gate structure, a post, a track having its middle portion depressed and pivoted to said post, the track extending in opposite directions from the post, means for limiting the downward movement of both ends of the track, a T-shaped lever pivoted at its upper end to said post and having a depending arm, a gate, hangers supporting the gate and having wheels operated on said track, one of said wheels normally resting in said depressed portion of the track, an oscillation of the T-shaped lever causing its arm to engage the wheel which is in said depression and lift said wheel onto the track and impel the gate toward one or the other end of the track, and a pair of flexible connections depending from each end of the lever, one of the flexible connections being disposed on one side of the gate and the other on the other side of the gate.

5. A gate structure of the character described comprising a pair of vertical posts, 105 a track having a depressed middle portion and pivoted between said posts at its middle, posts disposed beneath the ends of the track and vertically slotted to permit the ends of the track to be depressed into the slots to thereby limit the downward movement of the ends of the track, a gate adapted to move between said posts, hangers supporting the gate, wheels carrying the hangers and operating on the track, a T-shaped lever pivoted between said posts above the middle of the track and having a depending arm adapted to engage that wheel of the gate which is disposed in said depressed portion, 110 an oscillation of the lever acting to lift the wheel out of the depressed portion and impel the gate along the track, and manually operable means disposed on each side of the gate whereby the lever may be tilted.

In testimony whereof I hereunto affix my 125 signature.

CLYDE C. COOK.
